Marks + Clark

UNITED STATES PATENT OFFICE.

ALFRED C. JONASSEN, OF NEW YORK, N. Y., ASSIGNOR OF ONE-FOURTH TO HAROLD WILLIAM ANDERSON, OF AUCKLAND, NEW ZEALAND.

TOY PISTOL.

Application filed November 21, 1923. Serial No. 676,058.

To all whom it may concern:

Be it known that I, ALFRED CHRISTIAN JONASSEN, subject of the King of Great Britain, residing at New York city, county and State of New York, have invented certain new and useful Improvements in Toy Pistols, of which the following is a specification.

This invention relates to toy pistols for the projection of round objects such as marbles of the kind disclosed in my prior Patent No. 1,430,812, in which the marble is projected by a plunger adapted to reciprocate in the barrel and to which momentum is imparted for effecting the projection by means of a pivoted lever which is adapted to be actuated by means of a spring.

The object of the present invention is to provide a simplified mechanism for cocking the actuating lever and for releasing said lever when it is desired to project the marble or the like.

The construction of such mechanism is such that a single member, adapted to be conveniently operated by the finger of the operator is adapted to directly engage said actuating lever to move it into its cocked position in which such lever automatically locks itself by direct engagement with said member and then upon a further actuation of said member such member further engages said actuating lever to move it into a position whereby it may be actuated by the spring for effecting the operation of the plunger and the projection of the marble or the like.

In order that the invention may be clearly understood reference is made to the accompanying drawings which illustrate by way of example a preferred embodiment of the invention:

In the drawings:

Fig. 1 is a sectional elevation of the pistol showing the mechanism in the position assumed when all the parts are free.

Fig. 2 is a sectional elevation of the pistol showing the mechanism in the position assumed when the actuating lever is cocked, a modified form of actuating spring being shown.

Fig. 3 is a sectional elevation of the pistol showing the mechanism in the position assumed when the actuating lever has been moved out of its cocking position into the

position assumed immediately prior to its operation of the plunger, such lever also being shown in dotted lines in the position assumed immediately after the operation of the plunger.

Fig. 4 is a modified form of the actuating spring.

Figs. 5 and 6 are respectively side elevation and plan of a modified form of spring for holding the marble in position within the barrel.

The body portion of the pistol comprises a barrel 1 and a butt 2 and is preferably formed in two halves each of which is stamped out of sheet metal. The said halves are adapted to be connected together by means of a rivet 3 located substantially centrally of the butt 2 and by other additional means such as by the members 4 formed in the upper edge of one half of the barrel which are provided with slots 4^a adapted to receive cooperating members on the other half, and by the members 5 located on the lower edge of each half of the butt which are adapted to be bent over to engage the other half of the butt.

A spring member is provided within the barrel for maintaining the marble in the barrel and preventing the same from falling out if the pistol is pointed downwardly. This may be in the form of a leaf spring having a convex portion 6^a which is adapted to lightly engage the marble or the like as it is placed in the barrel, it may be of a hair pin formation as illustrated in Figs. 5 and 6 suitably curved as at 6^b and preferably provided with corrugations 6^c in one or other of which the marble or the like is adapted to fit according to its size and to be lightly held therein by the pressure of the spring.

The retaining spring is maintained in the barrel by any suitable means as by a hooked end portion 8 or bent portions 8^a engaging in slots 9 provided in the abutting edges of the two halves of the barrel.

The plunger 10 is provided with a longitudinal recess 11 adapted to accommodate the spring 6 and with a transverse slot 12 in which the upper end 13 of the actuating lever 14 is adapted to operate. The said plunger 10 may be made of wood as illustrated, in which case a pad 15 of resilient material is provided at the end thereof so

as to take the shock when striking the marble or the like and to minimize wear on the end of the plunger. If desired however the plunger may be formed out of stamped metal.

The mechanism for operating the plunger comprises the actuating lever 14 pivoted on the pin 3 and a slidable member 16 adapted to slide in a direction parallel to the barrel

10 1. In order to suitably restrict the movement of the member 16 to one parallel to the barrel 1 the forward end of such member 16 engages within recesses 17 provided in the abutting edges of the forward side of 15 the butt 2, and the rear portion of the said member 16 is provided with a slot 18 arranged longitudinally of said member in which the pin 3 is adapted to engage. The recesses 17 also prevent lateral movement 20 of the member 16 and the rearward part of slidable member 16 is also provided with downturned flanges 19 which slidably engage one of the side faces of the butt 2 and which also serve to prevent lateral movement 25 of such member 16.

The two members 14 and 16 are normally maintained in their forward positions as indicated in Fig. 1 by means of a spring 20, 20^a or 20^b mounted on the pivot pin 3 and 30 having one end 21 engaging a lug 22 on the lower edge of the member 16 and the other end engaging the actuating lever 14 either by a hook 15 embracing the rearward edge of said lever as illustrated in 35 Figs. 1-3 or by engaging a lug 23' on said actuating lever as illustrated in Fig. 4 of the drawings. The spring may either be of the simple form containing a single convolution encircling said pivot pin 15 as 40 illustrated in Figs. 1, 3 and 4 or may be of a spiral formation as illustrated in Fig. 2, and it is adapted also to maintain said members 14 and 16 in close contiguity. The upper edge of the slidable member 16 is provided with a recess 23 the forward 45 edge of which is in the form of a tooth 24 which is bent slightly so that it projects outwardly from that face of the member 16 which is adjacent the actuating lever 14. The forward end 25 of the slidable member 16 is shaped so that it may be conveniently 50 engaged by the finger of the operator and is also provided on the side thereof with a stop member 26 whose function will be described later. The forward edge 27 of the actuating lever 14 is cam shaped as indicated in the drawings, and is provided with a recess 28 forming a tooth shaped member 29 extending downwardly towards the lower 55 end of the butt 2 when the lever 14 assumes the position indicated in Fig. 2 of the drawings. The said tooth is also somewhat wedge shaped tapering towards its point so that it may engage behind the upper 60 edge of the slidable member 16 when the

said members assume a definite relative position as hereinafter described. A triangular shaped portion 30 of the said actuating lever 14, extending substantially across the entire width of said actuating 70 lever and located above the tooth 29 is embossed so as to leave a recessed portion on the side of such lever adjacent the slidable member 16.

Assuming that the members are in the 75 position indicated in Fig. 1, the operation of the device is as follows. The butt 2 is held in the hand of the operator in the usual manner and the end 25 of the slidable member 16 is engaged by the finger of the 80 operator so that a sliding movement is imparted to said member. At the beginning of this sliding movement the outwardly projecting tooth 24 on said member engages the cam surface 27 of the actuating lever 85 and thus owing to the movement imparted to said member 16 the actuating lever 14 is caused to turn upon its pivot 13 and to move the plunger 10 towards the rear of the barrel 1 simultaneously tensioning the spring 90 20. When, during this movement the point of the tooth 29 on the lever 14 clears the lower edge of the recess 23, then, if the pressure on the slidable member 16 is momentarily released, the said tooth 29, will 95 engage behind the edge of said recess and the sides of the recess 28 below said tooth 29 will embrace said edge and owing to the action of the spring 20 will frictionally engage the member 16 thus preventing a return movement of said member. The two members 14 and 16 will thus be locked together and the actuating lever maintained in its cocked position as illustrated in Fig. 2.

Upon further pressure being exerted upon the forward end of the slidable member by the finger of the operator, the tooth 24 on said slidable member which is still in engagement with the cam surface 27 of the lever 14 in a position above said recess 28, will impart a further pivotal movement to the lever 14 until the point of the tooth 29 on said lever rests upon the upper edge of the slidable member 16, whereupon, a further rearward movement of the slidable member 16 will cause the tooth 24 thereon to engage behind the said lever 14 as shown in Fig. 3, the edge of the recess 28 being slightly chamfered for this purpose and the said tooth 24 will thereby push the lever 14 away from the surface of the member 16 a slight extent, thus freeing the tooth 29 from the upper edge of the slidable member and permitting the spring 20 to impart to said lever a rapid pivotal movement 115 120 which is arrested by the cam surface thereon engaging a correspondingly shaped surface on the stop 26 hereinbefore mentioned. A rapid forward movement will thus be imparted to the plunger 10 which will strike 125 130

the marble 7 which has previously been placed in the barrel 1, and will project the same.

As will clearly be seen from Fig. 3 of the drawings the return movement of the actuating lever 14 is arrested by the stop 26 and not by the metal of the casing or body of the pistol, and damage to such casing is thereby obviated. Also during the return movement of the said lever the outwardly projecting tooth 24 on the slidable member 16 will be situated in the recess behind by the embossed portion 30 on the lever 14 and thus will not be in frictional engagement with said lever.

After the projection of the marble or the like the pressure on the slidable member 16 is released whereupon the spring 20 will return the same into the position shown in Fig. 1, the tooth 24, owing to its wedge shape, freely passing beneath the edge of the embossed portion 30, and thus assuming a position adapted to engage the cam surface 27 of the lever 14 upon a further actuation of the slidable member 16 by the operator.

As is clearly shown, the various parts of the structure forming the pistol are few in number and of simple formation all of them with the exception of the spring being adapted to be stamped out of sheet metal. Also the parts may be easily assembled. Thus it is obvious that the cost of construction of the device will be comparatively low.

What I claim is:—

1. A toy pistol comprising a barrel, a plunger within said barrel, a pivotal actuating lever for said plunger, a member adapted to be moved relatively to said actuating lever, a spring associated with said actuating lever, means whereby said member is adapted upon an initial movement thereof to directly engage said lever and thereby to move the same into a cocked position and to impart tension to said spring, means whereby said actuating lever is adapted to directly engage said member when it is moved into its cocked position and thereby to mutually lock itself and said member in such position, and means whereby said member is adapted on further actuation thereof to further directly engage said actuating lever and thereby to move it into such a position that it may be freely actuated by said tensioned spring to effect the operation of said plunger.

2. A toy pistol comprising a barrel, a plunger within said barrel and means for actuating said plunger comprising two co-acting members and a spring associated with such members, such members being so related that a movement imparted to one of such members will first effect the tensioning of said spring and cause the direct engage-

ment of the two members and thereby effect the movement of said other member into a locked cocking position and will then cause a further direct engagement of the two members and thereby effect the movement of said other member into a position in which it can be freely actuated by said tensioned spring to effect the operation of said plunger.

3. A toy pistol comprising a barrel, a plunger within said barrel, means within said barrel for holding a projectile within such barrel preparatory to the projection thereof, a pivotal actuating lever for said plunger a member adapted to be moved relatively to said actuating lever, a spring associated with said actuating lever, means whereby said member is adapted upon an initial movement thereof to directly engage said lever and thereby to move the same into a cocked position and to impart tension to said spring, means whereby said actuating lever is adapted to directly engage said member when it is moved into its cocked position and thereby to mutually lock itself and said member in such position, and means whereby said member is adapted on further actuation thereof to further directly engage said actuating lever and thereby to move it into such a position that it may be freely actuated by said tensioned spring to effect the operation of said plunger.

4. A toy pistol comprising a barrel, a plunger within said barrel, a curved spring within said barrel adapted to hold a projectile within said barrel preparatory to the projection thereof, a pivotal actuating lever for said plunger, a member adapted to be moved relatively to said actuating lever, a spring associated with said actuating lever, means whereby said member is adapted upon an initial movement thereof to directly engage said lever and thereby to move the same into a cocked position and to impart tension to said spring, means whereby said actuating lever is adapted to directly engage said member when it is moved into its cocked position and thereby to mutually lock itself and said member in such position, and means whereby said member is adapted on further actuation thereof to further directly engage said actuating lever and thereby to move it into such a position that it may be freely actuated by said tensioned spring to effect the operation of said plunger.

5. A toy pistol comprising a barrel, a plunger within said barrel, a pivotal actuating lever for said plunger, a slidable member adapted to be moved relatively to said actuating lever a spring adapted to maintain such member and such lever in their inoperative positions, a cam shaped edge on said actuating lever, an outwardly projecting member on said slidable member adapt-

ed to engage said cam shaped edge when an initial movement is imparted to said slideable member and thereby to move said operating lever about its pivotal axis, means on said slideable member and on said actuating lever adapted to impart tension to said spring upon such initial movement of said slideable member, means on said actuating lever adapted to engage said slideable member when the actuating lever is moved into its cocked position thereby mutually locking such lever and member in such position, and means whereby on a further actuation of said slideable member said outwardly projecting member on said slideable member will actuate said actuating lever so as to move it from its locking position and then move it into such a position that it may be freely actuated by said tensioned spring to effect the operation of said plunger.

6. A toy pistol comprising a barrel, a plunger within said barrel, a curved spring within said barrel having corrugations therein adapted to hold a projectile within said barrel preparatory to the projection thereof, a pivotal actuating lever for said plunger, a member adapted to be moved relatively to said actuating lever, a spring associated with said actuating lever, means whereby said member is adapted upon an initial movement thereof to directly engage said lever and thereby to move the same into a cocked position and to impart tension to said spring, means whereby said actuating lever is adapted to directly engage said member when it is moved into its cocked position and thereby to mutually lock itself and said member in such position, and means whereby said member is adapted on further actuation thereof to further directly engage said actuating lever and thereby to move it into such a position that it may be freely actuated by said tensioned spring to effect the operation of said plunger.

7. A toy pistol comprising a barrel, a plunger within said barrel, a curved spring of hair pin shape having corrugations in each leg thereof adapted to hold a projectile within said barrel preparatory to the projection thereof, a pivotal actuating lever for said plunger, a member adapted to be moved relatively to said actuating lever, a spring associated with said actuating lever, means whereby said member is adapted upon an initial movement thereof to directly engage said lever and thereby to move the same into a cocked position and to impart tension to said spring, means whereby said actuating lever is adapted to directly engage said member when it is moved into its cocked position and thereby to mutually lock itself and said member in such position, and means whereby said member is adapted on further actuation

thereof to further directly engage said actuating lever and thereby to move it into such a position that it may be freely actuated by said tensioned spring to effect the operation of said plunger.

8. A toy pistol comprising a barrel, a plunger within said barrel, a pivotal actuating lever for said plunger, a slideable member adapted to be moved relatively to said actuating lever, a spring normally adapted to maintain such member and such lever in their inoperative positions; a cam shaped edge on said actuating lever, an outwardly projecting member on said slideable member adapted to engage said cam shaped edge when an initial movement is imparted to said slideable member and thereby to move said operating lever about its pivotal axis, means on said slideable member and on said actuating lever adapted to impart tension to said spring upon such initial movement of said slideable member, a wedge shaped tooth shaped member in said cam shaped edge of the actuating lever adapted to engage the rear side of the upper edge of the slideable member when the actuating lever is moved into its cocking position and the pressure on said slideable member is relieved thereby frictionally engaging said slideable member and mutually locking the said member and said lever in said cocked position, and means whereby said outwardly projecting member on said slideable member will actuate said actuating lever so as to move it from its locking position and then move it into such a position that it may be freely actuated by said tensioned spring to effect the operation of said plunger.

9. A toy pistol comprising a barrel, a plunger within said barrel, a pivotal actuating lever for said plunger, a slideable member adapted to be moved relatively to said actuating lever, a spring normally adapted to maintain such member and such lever in their inoperative positions; a cam shaped edge on said actuating lever, an outwardly projecting member on said slideable member adapted to engage said cam shaped edge when an initial movement is imparted to said slideable member and thereby to move said operating lever about its pivotal axis, means on said slideable member and on said actuating lever adapted to impart tension to said spring upon such initial movement of said slideable member, a wedge shaped tooth shaped member in said cam shaped edge of the actuating lever adapted to engage the rear side of the upper edge of the slideable member when the actuating lever is moved into its cocking position and the pressure on said slideable member is relieved thereby frictionally engaging said slideable member and mutually locking the said member and said lever in said cocked position, and means whereby said outwardly

projecting member on said slidable member will, upon further movement of said member actuate such lever so that the tooth thereon is moved out of its locking position 5 and then moved so that it is clear of said slidable member so that said lever may be freely actuated by said tensioned spring to effect the operation of said plunger.

10. A toy pistol comprising a barrel, a plunger within said barrel, a pivotal actuating lever for said plunger, a slidable member adapted to be moved relatively to said actuating lever and arranged with a side face thereof in close contiguity with said 15 actuating lever, a spring normally adapted to maintain said member and said lever in their inoperative positions and in contiguous relation, a cam shaped edge on said actuating lever, a tooth shaped member on said slidable member projecting outwardly from that face thereof which is adjacent said actuating lever, such tooth shaped member being adapted to engage said cam shaped edge when an initial movement is imparted to said slidable member and thereby to move said operating lever about its pivotal axis, means on said slidable member and on said actuating lever adapted to impart tension to said spring upon such initial movement of said slidable member, a wedge shaped tooth shaped member in said cam shaped edge of the actuating lever adapted to engage the rear side of the upper edge of the slidable member when the actuating lever is moved into its cocking position and the pressure on said slidable member is relieved thereby frictionally engaging said slidable member and mutually locking the said member and said lever in said cocked position, means whereby said tooth shaped member on said slidable member will, upon further movement of said member actuate such lever so that the tooth thereon is moved out of its locking position and then moved so that it is clear of said slidable member 20 so that the said lever may be actuated by said tensioned spring to effect the operation of said plunger, and an embossed portion on said actuating lever adapted to accommodate within the recess formed at the rear thereof the outwardly projecting tooth shaped member on the slidable member during the said operative movement of said actuating lever.

In testimony whereof I affix my signature in presence of two witnesses. 25

ALF. C. JONASSEN.
